UNITED STATES PATENT OFFICE.

JOHN C. WHITMER, OF LORDSBURG, CALIFORNIA.

PUMP DRIVING MECHANISM.

No. 877,276.

Specification of Letters Patent.

Patented Jan. 21, 1908.

Application filed May 1, 1907. Serial No. 371,328.

To all whom it may concern:

Be it known that I, JOHN C. WHITMER, a citizen of the United States of America, residing at Lordsburg, in the county of Los Angeles and State of California, have invented new and useful Improvements in Pump Driving Mechanism, of which the following is a specification.

This invention relates to driving mechanism for double-acting pumps, and is designed as an improvement upon the driving mechanism shown in my prior patent No. 753,771 dated March 1, 1904, the present invention providing a more efficient connection between the crank gears and levers to sustain the working strain.

In the accompanying drawing:—Figure 1 is a side elevation of the driving mechanism. Fig. 2 is a top plan view thereof. Fig. 3 is a detail section.

Referring to the drawing, the numeral 1 designates a frame, on which are eccentrically pivoted I-beam levers 2, pivotally connected at the forward ends of their short arms to the pump rods 3. On the frame is mounted a drive shaft 4, on one end of which is fixed a pulley 5 for connection with a drive belt. On said shaft are also revolvably mounted pinions 6, which mesh with gear wheels 7 mounted in bearings secured to the frame. These gear wheels, as shown, are mounted on shafts 8, each journaled in two bearings 9 on the frame, but only one bearing for each shaft is necessary. These gear wheels carry crank pins 10, which carry blocks 11, slidably engaging the upper heads of the levers, said blocks being provided with dovetailed tongues 12, engaging under the lateral flanges 13 of said heads. This construction is superior to that shown in my patent referred to, as the I-beam formation of the levers dovetailed connection between the blocks and upper flanges of said levers insures a stronger construction, truer guiding contact and a firmer coupling engagement to withstand the strain.

It will be observed that the lateral flanges 13 extend to the outer or free end of the beam 2, and that the inwardly extending tongues 12 of the block are integral with the block and are spaced a sufficient distance to lie out of contact with the body or web of the beam while forming guide grooves of sufficient width to receive the edges of the flanges. This construction allows the block 11 to be readily slipped on and off the free end of the

beam 2 and obviates the necessity of providing detachable securing devices to enable the block to be removed and applied and held in operative position.

The crank pins are arranged on the opposite sides of the gear wheel, so that in the rotation of the gears one of the levers is at the end of its upward movement when the other is at the extreme limit of its downward movement. The distance from the fulcrum of these levers to the end of the movement of the sliding block is preferably twice as great as the distance from the fulcrum to where the pump rods are connected. By this arrangement, when power is applied to drive levers, the strain of lifting the pump rods commences and is completed during the time that the sliding blocks are going outward or away from the fulcrum and back to the point at which the crank pin reaches a line which runs tangent from the fulcrum to the path of revolution of the crank pin.

The downward movement is effected during the remainder of the movement of the crank pin: As the downward movement is accomplished in less time by the slide block coming closer to the fulcrum, at every stroke, both move upward together a short space, thereby always insuring a constant motion in the upward flow of water.

Having thus described the invention, what is claimed as new, is:—

In a driving mechanism, a frame, two levers pivotally mounted thereon, said levers being of I-form in cross section, reciprocating rods operated by the short arms of the levers, the long arms of said levers having their lateral flanges extending continuously to the free ends thereof, operating gears carrying oppositely arranged crank pins, means for actuating said gears, and blocks carried by said pins, and sliding upon the upper flanges of the levers, said blocks being provided with integral tongues projecting inwardly beneath said upper flanges and forming guide grooves receiving the same, said blocks being adapted when released from the wrist pins to be slid longitudinally on and off said flanges at the free ends of the levers.

In testimony whereof, I affix my signature in presence of two witnesses.

JOHN C. WHITMER.
